Primary Examiner — Susan B Hattan*Assistant Examiner* — Leanne D Was-Englehart(74) *Attorney, Agent, or Firm* — Seager Tufte & Wickhem LLP(57) **CLAIM**

The ornamental design for a humidifier user interface, as shown and described.

DESCRIPTION

FIG. 1 is a front side view of a steam humidifier with a humidifier user interface, the steam humidifier housing shown in broken lines; and,

FIG. 2 is an enlarged view of the humidifier user interface of FIG. 1.

The broken lines depict the environment for the claimed design and form no part of the claimed design.

1 Claim, 2 Drawing Sheets(56)
